J. PEGEL.

RUG.

N° 17,099.

Patented Feb. 8, 1887.

A

UNITED STATES PATENT OFFICE.

JULIUS PEGEL, OF CAMDEN, NEW JERSEY, ASSIGNOR TO JOHN BROMLEY & SONS, OF PHILADELPHIA, PENNSYLVANIA.

DESIGN FOR A RUG.

SPECIFICATION forming part of Design No. 17,099, dated February 8, 1887.

Application filed January 5, 1887. Serial No. 223,489. Term of patent 3½ years.

To all whom it may concern:

Be it known that I, JULIUS PEGEL, a subject of the Emperor of Germany, residing at Camden, county of Camden, and State of New Jersey, have invented and produced a new and original Design for a Rug; and I do hereby declare that the photographic print accompanying this specification conveys to any one skilled in the art a clear understanding of the same, and is sufficient to enable such person to use my invention.

The leading feature of my design consists in a center medallion, upon which is a floral representation of a bunch of asters. At each end of the rug is a narrow panel, upon which are massed floral representations. At the top and bottom is a border formed of scrolls. The whole is surrounded by an ornamental border, as shown.

What I claim as my invention is—

The design for a rug, consisting of a center medallion upon which is shown a bunch of asters, and at each end is shown a narrow panel upon which are massed floral representations, and at the top and bottom is a border formed of scrolls, the whole surrounded by an ornamental border, as shown.

JULIUS PEGEL.
